UNITED STATES PATENT OFFICE

ALBERT J. MYERS, OF PITTSBURGH, PENNSYLVANIA, ASSIGNOR TO THE KOPPERS COMPANY, OF PITTSBURGH, PENNSYLVANIA, A CORPORATION OF PENNSYLVANIA

ROTARY GRIZZLY

Application filed July 3, 1925. Serial No. 41,420.

This invention comprehends improvements of general utility in the art of screening coke and in its more particular aspects relates to a special arrangement of the driving mechanism with respect to the operating shafts of the so-called "grizzly" so as to permit ready removal of any shaft of the "grizzly" for repairs without disturbing the driving mechanism or the removal of parts of the driving mechanism without disturbing the "grizzly" while maintaining at all times an efficient lubrication of the driving mechanism and protecting it from the coke dust.

In the preparation of coke for the market it is essential to screen out the finer particles therefrom and this can be most efficiently and quickly achieved by the use of the so-called "grizzly" comprising an inclined frame-work carrying a plurality of parallel shafts on which are non-rotatably mounted hard cast iron discs, the peripheries of the discs of one shaft inter-meshing with those on the next adjacent shafts leaving restricted spaces at the ends of the peripheries for the sifting out of the finer particles of coke. The motion of the coke is substantially forward and downward, there being an undulating or cascade movement imparted thereto by the peripheries of the discs and the stream of coke is ordinarily attenuated towards the lower end by increasing the speeds of the successive shafts from top to bottom. Such a construction has higher capacity than any other known type of screen and is in fact the most practical way in which large sizes of coke may be efficiently screened. However, the larger particles of the material to be screened out frequently catch and stick in the open spaces between the inter-meshing discs and due to their very hard character—relatively much harder than is possible to make the cast iron discs—cause abrasion and wear of the latter resulting in a material enlarging of the screening spaces and a substantial variation in the degree of uniformity of grading of the material unless corrected. The wearing action is greatest at the top and decreases towards the bottom due to the fact that the major portion of the screening operation is accomplished in the upper regions. When the

upper discs become sufficiently worn to materially affect the standard of the screening correction is in general made either by shifting the shafts and their attached discs from the lower portion of the screen to the upper and from the upper to the lower, or by replacement of the worn discs by new ones, or replacements may be made after the first shift whenever it becomes desirable, all of which operations necessitate the removal of the shafts. As heretofore practiced, it has been customary to permanently mount the driving mechanism for the shafts on the ends of the latter outside of their bearings, but this necessitated, when the shafts were shifted or replacements made, the removal of the portion of the driving mechanism attached to the shaft or shafts removed from the rest of the driving mechanism even though the driving connections between the several shafts were in good order and well lubricated. The disturbance of these connections made it necessary to re-lubricate the driving mechanism when again set up and rendered it liable to the introduction of destructive coke dust. It also made it necessary to tear down the oil casing every time a shaft was removed, all of which resulted in inefficiency and loss since it is necessary to make repairs as quickly as possible in order to cut down the "shut down" period of the plant.

My invention contemplates, broadly, expedients for overcoming all of these difficulties. This I accomplish by removing the driving mechanism from its position adjacent the bearings of the shafts and mounting it in an individual casing spaced apart from the ends of said shafts. The driving mechanism may conveniently consist of a plurality of counter-shafts connected to each other within said casing by appropriate gears, or chains and sprockets, or other connecting mechanism, the counter-shafts being connected to the main shafts with which they are respectively in alignment by appropriate coupling members which permit ready uncoupling of the main shaft from the counter-shaft when it is desired to remove the former for replacement or repairs. A further feature of my invention consists in providing an

oil tight casing for the driving mechanism separate from the main frame of the "grizzly" and preferably provided on its bottom with a plurality of baffles or dams forming pockets for the retention of oil into which the driving connections between the several counter-shafts may dip and thus effect the necessary lubrication of the driving mechanism. If desired, similar baffles may be placed in said casing above the driving mechanism in the path of oil thrown off by centrifugal force to facilitate equalization in distribution of oil throughout the casing. When the counter-shafts are connected by gears and idlers, the direction of rotation of the idlers is such as to pump oil out of the pockets, over the dams, and to the bottom of the casing. I therefore preferably provide the casing with means for pumping the oil from the lower end thereof to the upper end to maintain its circulation throughout the casing. The top of the casing may be provided with removable covers or doors to permit inspection.

In addition to the general features and objects of the invention above recited, the invention has such other improvements or advantages in construction and operation as are found to obtain in the structure and devices hereinafter described or claimed.

In the accompanying drawings, forming a part of this specification, and showing for purposes of exemplification a preferred form and manner in which the invention may be embodied or practiced, but without limiting the claimed invention specifically to such illustrative instance or instances:

Figure 1 is a top plan view of a "grizzly" embodying the features of my invention, taken from the line 1—1 of Fig. 2, with a portion of the driving casing removed and showing the "grizzly" discs partly broken away,

Fig. 2 is an end view partly in section, on the line 2—2, Fig. 1, showing the casing for the driving mechanism and its supports,

Fig. 3 is a detail perspective view of the preferred form of coupling employed by me, showing the parts separated,

Fig. 4 is a similar view showing the parts assembled,

Fig. 5 is a plan view of a modified form of my invention with the top of the driving casing removed, showing a chain and sprocket drive therein,

Fig. 6 is a vertical section through the casing on the line 6—6 of Fig. 5, and

Fig. 7 is a transverse vertical section on the line 7—7 of Fig. 6, showing a counter-shaft and its two sprockets.

The same characters of reference indicate the same parts in each of the several views of the drawings.

Referring to Fig. 1 there is shown a "grizzly" 1 provided with supporting frames

2 adapted to support the same at an inclination as shown in Fig. 2. Within these frames are journaled a plurality of parallel shafts 3 on which are non-rotatably mounted a series of discs 4, the peripheries of the discs of each shaft being inter-leaved with those of the adjacent shafts, free spaces existing at the ends of the discs of appropriate size for the passage of the finer particles of coke which it is desired to separate from the main body thereof. These shafts 3 are journaled at their opposite ends in bearings having their upper parts 5 removable to permit removal of the shafts together with the discs thereon for repair or replacement. Located just inside of the bearings on each side are coke guide-plates 6 for confining the coke laterally. The shafts, as has heretofore been the custom, are driven from a common source of power through inter-connected gears between the several shafts, or by chains and sprockets. In accordance with prior practice, the driving gears or sprockets were permanently directly connected to the ends of the shafts, necessitating, as hereinbefore noted, the dismembering of the driving mechanism when it was desired to change or repair a set of discs. I, however, construct each shaft and its discs as a unit removable independently of the driving mechanism without the necessity of disturbing the latter. To accomplish this result I connect each shaft through a separable coupling 7 with a corresponding counter-shaft 8 and mount all of said counter-shafts in a separate casing distinct and apart from the bearing supports for the corresponding main shafts, one of the counter-shafts 9 being connected to the source of power and all of the counter-shafts being supported in separable bearings 10 in the casing 11. These counter-shafts may be inter-connected respectively by sets of driving gears 13 and driven gears 13' inter-connected by idlers 14.

The separable coupling 7, in order to satisfy the special conditions met with in constructions of this character, preferably consists of three parts—15, 16 and 17. The part 15 is connected by its collar 18 to the end of a main shaft and its body portion 19 is provided diametrically across its face with a channel 20 and in contact with the body 19 is adapted to rest a floating intermediate part 21 provided with a tongue 22 diametrically across its face adapted to seat in the channel 20 and on the opposite face of the member 21 is provided diametrically a second tongue 23 preferably at right angles to the first adapted to seat in the corresponding channel 26 in the face of the body member 25 of the third coupling member 17, the latter being provided with a collar 24 by which it is non-rotatably secured to a counter-shaft by the key-way 27. If desired, the floating member 21 may be made integral, say, with the body 13.

member 25, one removable tongue and channel connection alone being sufficient to permit quick removal of a shaft. Either arrangement here indicated, while per se old, has a special utility in my construction since it obviates the necessity of removing bolts or nuts, thus facilitating the quick and convenient removal of a shaft. Moreover, the floating member, when employed, additionally effects an efficient drive even though the shaft and its counter-shaft be not in exact alignment.

The casing of the driving mechanism, as a further feature of my invention, is preferably made oil and dust tight and is divided into a lower part 30 and an upper removable part 31 connected by bolts 33 and provided with oil tight hinged covers 34 to permit inspection. The bottom of the lower casing section 20 is provided, intermediate the idler gears 14, with upstanding baffles or dams 35 adapted with the bottom to form pockets into which the oil may settle and into which the idlers dip. Further baffles 36 are provided in the 25 upper casing section intermediate the driving and driven gears 13 and 13', and since the idlers 14, as shown in Fig. 2, normally rotate in a counter-clockwise direction and thereby tend to pump oil out of the pockets, causing it to descend to the bottom of the casing, I preferably employ an oil return pipe 27 connected to the bottom of the casing through which the oil is pumped by a pump 38 and a pipe 39 into the upper end of the 35 casing thereby maintaining continuous the flow of oil therethrough.

In Figs. 5, 6 and 7, is shown a modified form of drive, consisting of driving sprockets 50 and driven sprockets 51 on the 40 counter-shafts connected respectively in pairs by chains 52, the consecutive chain drives being connected in offset staggered or overlapping relation as shown in Fig. 6. I provide an oil pocket for each chain drive 45 in corresponding overlapping relationship by extending from the bottom of the casing walls or dams 53, and since in a chain drive, the chain passes through the oil in a reverse direction to the motion of the idlers in Fig. 50 2 or clockwise they tend to carry the oil up the incline and maintain the several pockets filled therewith, thus obviating the necessity of using an oil pump and return pipes from the bottom to the top of the oil casing although the latter may, of course, be employed if desired.

In the operation of the device, when it is desired to remove a main shaft for replacement or repair of the discs therein, the bearing caps 5 are removed which permits the shaft to be lifted, the coupling 7 being rotated until one of the tongue and channel pairs assumes a substantially vertical position when it is readily separated without 55 interference in any manner with the driving

mechanism. The latter mechanism and its casing comprise a self-contained unit in which the driving mechanism proper and its lubricating medium are at all times protected against grit and dust by reason of its closed casing, and this condition also prevails regardless of the extent to which it may become necessary to repair or replace parts of the "grizzly" unit proper. Moreover, the rotation of the idlers 14 or the chains 52 in their respective oil pockets effects a continuous feed of the oil to the driving mechanism maintaining a uniform lubrication of the latter. The uniformity of lubrication in the case of the idlers may be further enhanced 75 by the use of the oil pump 38 and the return oil flow pipes 37 and 39 leading from the bottom of the case to the top thereof, and by the further use of baffles 36 between the gearing on the counter-shafts. Should it be necessary to repair the driving mechanism this also may readily be accomplished without disturbing the "grizzly" mechanism.

The features of the inclined series of oil holding compartments form the subject matter of my co-pending divisional application Serial No. 496,389, filed November 18, 1930, and entitled Rotary grizzly.

The invention as hereinabove set forth is embodied in a particular form of construction but may be variously embodied within the scope of the claims hereinafter made.

I claim:

1. In a rotary grizzly structure, the combination with an inclined series of rotary screening roller shafts mounted for removal from the series independently of each other and respectively having rotary screening rollers fixed thereon for rotation therewith of an inclined series of counter-shafts, driving mechanism for said shafts separate from and independent of said rotary screening roller shafts, and separable connections between said counter-shafts and said rotary screening roller shafts; whereby the rotary screening rollers may be removed from and shifted to different locations in the grizzly structure by shifting of their respective rotary screening roller shafts without dismantling of the driving mechanism or altering the rate of rotation of the rotary screening rollers intended in the location in the said series to which they are shifted.

2. In a rotary grizzly structure, the combination with an inclined series of rotary screening roller shafts mounted for removal from the series independently of each other and respectively having rotary screening rollers fixed thereon for rotation therewith of an inclined series of counter-shafts, driving mechanism for said shafts separate from and independent of said rotary screening roller shafts, separable connections between said counter-shafts and said rotary screening roller shafts, and a dust-proof casing enclos-

- ing the driving mechanism and located beyond the separable connections; whereby the rotary screening rollers may be removed from and shifted to different locations in the grizzly structure by shifting of their respective rotary screening roller shafts without dismantling of the driving mechanism or altering the rate of rotation of the rotary screening rollers intended in the location in the said series to which they are shifted.
3. In a rotary grizzly structure, the combination with an inclined series of rotary screening roller shafts mounted for removal from the series independently of each other and respectively having rotary screening rollers fixed thereon for rotation therewith of an inclined series of counter-shafts, driving mechanism for said shafts separate from and independent of said rotary screening roller shafts, separable connections between said counter-shafts and said rotary screening roller shafts, and a dust-proof lubrication casing enclosing the driving mechanism and located beyond the separable connections; whereby the rotary screening rollers may be removed from and shifted to different locations in the grizzly structure by shifting of their respective rotary screening roller shafts without dismantling of the driving mechanism or altering the rate of rotation of the rotary screening rollers intended in the location in the said series to which they are shifted.

In testimony whereof, I have hereunto set
35 my hand.

ALBERT J. MYERS.
